SEWING MACHINE

Max L. Waterman, Fairfield, Conn., assignor to
 The Singer Manufacturing Company, Elizabeth,
 N. J., a corporation of New Jersey

Application December 16, 1936, Serial No. 116,078

8 Claims. (Cl. 112—54)

This invention relates to improvements in sewing machines and has for its primary object to provide means for effecting the production of 5 stitched seams closely simulating so-called moccasin seams.

The invention consists in the combination, with the stitch-forming and work-feeding mechanisms of a sewing machine, of bead-forming and scoring devices as hereinafter described in connection 10 with the accompanying drawings which illustrate one embodiment of the invention and in which—

Fig. 1 is a front side elevation, partly in section, of a portion of a sewing machine containing the present improvement. Fig. 2 is a front end elevation of the bracket-arm head of the sewing machine, with the face-plate partly broken away and the throat-plate and drop-feed mechanism illustrated fragmentarily. Fig. 3 represents a horizontal section of the bracket-arm head, taken 15 substantially on the line 3—3 of Fig. 2. Fig. 4 represents, in perspective, the throat-plate and bead-scoring knife in the cooperative relation of the knife and a bead-forming rib or finger upon the throat-plate. Fig. 5 represents in vertical 20 section the throat-plate, the work thereupon, the feeding elements and the bead-scoring knife, the section being taken substantially in the vertical plate containing the two needles. Fig. 6 represents in perspective view of the presser-foot. Fig. 25 7 represents, in perspective, a fragmentary representation of a shoe-vamp provided with the improved imitation moccasin seam.

Referring to the drawings, the present invention is illustrated as embodied in a sewing machine having a frame comprising a bed-plate 1 and a hollow bracket-arm 2 overhanging the bed-plate, the bracket-arm 2 terminating at its free 30 end in a head 3 to which a face-plate 4 is detachably secured by a screw 5.

40 Rotatably journaled in the bracket-arm 2 is the main actuating shaft 6 of the machine, said shaft carrying at one end a crank-disk 7 connected by the usual link 8 with a vertically reciprocating needle-bar 9 journaled in the head 3. At its lower end, the needle-bar 9 carries a 45 pair of needles 10 preferably disposed abreast with respect to the line of feed of the work. Co-operating with both of the needles 10 is a rotary shuttle 11 disposed at the underside of the bed-plate 1, said shuttle rotating in a vertical plane 50 transverse to the line of feed and functioning to seize both of the thread-loops presented by the two needles and to carry said thread-loops about a mass of under-thread within a thread-case 12. As the stitch-forming mechanism re-

ferred to is well known in the art, a detailed description thereof is deemed unessential to an understanding of the present invention.

Suitably secured upon the bed-plate 1 is a throat-plate 13 provided with feed slots 14, and with a needle-slot 15 which is elongated transversely of the line of feed and is entered by both of the needles 10. Operating through the feed-slots 14 is the feed-dog 16 of a drop-feed mechanism which may be of any usual or suitable 10 character.

Opposed to the feed-dog 16 is an alternating-presser mechanism including an upper feeding-foot 17 and a presser-foot 18. The feeding-foot 17 is forked to provide laterally spaced work-engaging members 17' and 17'' disposed outside of the needles, said feeding foot being adjustably secured by a screw 19 to the lower end of a vertically disposed feed-bar 20. Adjacent its upper end, the feed-bar 20 is pivotally secured by a screw 21 to one arm 22 of a bell-crank lever 22, 23, said lever being fulcrumed upon a screw 24 threaded horizontally into an arm 25 extending laterally from a collar 26 suitably secured upon a presser-bar 27. The other arm 23 of said bell-crank lever is connected by a link 28 to a crank-arm 29 carried by the crank-disk 7. A spring 30 has one end connected to the lever-arm 23 and its other end to an extension of the feed-bar 20 above the pivot-screw 21, said spring 30 functioning to effect return swinging movements of the feed-bar 20 when the feeding-foot 17 is lifted clear of the work. The return swinging movements of the feed-bar 20, under the influence of the spring 30, are limited by an angular stop-plate 31 adjustably secured by screws 32 upon a collar 33 fixed upon the presser-bar 27.

The presser-foot 18 is secured to the lower end of the presser-bar 27 in the usual manner, said presser-bar being journaled in the head 3 for vertical movement and being yieldingly depressed by a spring 34. The alternating-presser mechanism described operates in a manner well known in the art, it being understood that the presser-foot 18 holds the work against movement during 45 the return movement of the feeding foot 17, and that said presser-foot is lifted clear of the work when the feeding foot is lowered into engagement with the work.

The presser-foot 18 is bifurcated to provide 50 laterally spaced work-engaging members 18' and 18'', affording a clearance therebetween for the work-bead and for the bead-scoring knife hereinafter described. The work-engaging members 55 of the presser-foot 18 are disposed between the

feeding-foot members 17' and 17'', said presser-foot members having needle-apertures 35 aligned with needle-clearance grooves 36 in the opposed side faces of the presser-foot members.

5 Rising from the throat-plate 13, in front of the needle slot 15 therein, is a bead-forming rib 37 disposed medianly between and spaced from the presser-foot members 18', 18'', said rib having its rearward end also spaced from the throat-plate to overhang the needle-slot 15. The crest of the rib 37 extends lengthwise in the line of feed of the work and is preferably inclined upwardly from the front end thereof, thereby to gradually form a ridge or bead in the work as it is advanced to the needles, it being understood that the vertically reciprocatory presser-foot 18 coacts with the rib 37 to ridge the work and thereby form a bead therein.

Preferably opposed to the crest of the rib 37 and spaced slightly above said crest is the lower end of a bead-scoring knife-blade 38 depending from a rearward extension 39 of the knife-shank 40, the lower or point-end of the knife-blade 38 being provided with a cutting edge parallel to the rib 37. The shank 40 of the bead-scoring knife is secured by screws 41 to the lower end of a knife-bar 42 confined to endwise vertical movement by opposed guide-walls formed in the bracket arm head 3 and the face-plate 4, as illustrated in Fig. 3 of the drawings. The lower end of the knife-bar 42 is preferably additionally steaddied against lateral movement by a suitably recessed guide-bar 43 extending forwardly from a collar 44 fastened upon the presser-bar 27. Adjustably secured upon the upper end of the knife-bar 42 is a stop-collar 45 which limits downward movement of the knife-bar under the action of a spring 46 of which one end is connected to the knife-bar and the other end to the machine frame.

Between its ends, the knife-bar 42 is formed with a shoulder 47, and below this shoulder is disposed an ear 48 bent laterally from a thread-tension releasing member 49. As usual, the member 49 is secured by screws 50 to a collar 51 slidably embracing the presser-bar 27, said collar having a laterally extending arm 52 disposed between the usual presser-bar lifter-arm 53 and the manually operable lifter-lever 54 upon the machine head 4. Consequently, the knife 38 may be shifted out of the operative position thereof by actuation of the manually operable lifter-lever 53.

While also adapted for other purposes, the present improvement is particularly useful in making imitation moccasin seams in shoe vamps, a finished seam as produced by the means above described being illustrated in Fig. 7 of the drawings, in which A represents the body material such as a shoe-vamp; B, the bead; C, the score cut into the crest of the bead B; S, the two needle-threads penetrating the shoe-vamp at opposite sides of the bead B; and S', the shuttle-thread concatenated with both of the needle-threads S.

When forming the seam, the body material A passes over the throat-plate rib 37, the presser-foot being raised clear of the work during the advancing movement thereof effected by the combined action of the feed-dog 16 and the feeding-foot members 17', 17''. The scoring-knife 38 is normally so disposed that its spacing from the crest of the rib 37 is less than the thickness of the body material A and, consequently, a thin slit is progressively cut into the upper face

of the body material A as it is intermittently advanced. Each advancing movement of the work is succeeded by a downward work-clamping movement of the presser-foot 18, thereby bending the work about the rib 37 and forming a ridge or bead therein. This bending of the work is facilitated by the slit or score cut into the upper face of the work, the slit or score opening up to accommodate the sharp bending of the work. The needles descend at opposite sides of the work and closely adjacent to the rib 37 while the work is clamped by the presser-foot, and the concatenation of the two needle-thread loops below the work by the shuttle thread S' secures the ridged work so as to maintain the previously formed bead. It will be noted that the opened score C in the bead closely simulates the upturned edges of a moccasin seam and while it is preferred to arrange the cutter so as to be opposed to the crest of the rib 37 to score the work at the point where it is ridged, it will be obvious that the cutter may be disposed in front of said rib to score the work preparatory to but in the bead-forming operation.

Having thus set forth the nature of the invention what I claim herein is:

1. In a sewing machine, a work-support, work-feeding means, stitch-forming mechanism including a pair of vertically reciprocatory needles spaced laterally of the line of feed of the work, a ridge-forming rib disposed upon said work-support between the paths of reciprocation of said needles and extending in the line of feed, a work-presser opposed to said work-support at opposite sides of said rib, and a ridge-scoring knife having its cutting edge opposed to and spaced from the crest of said rib.

2. In a sewing machine, a work-support, work-feeding means, a ridge-forming rib disposed upon said work-support, a work-presser opposed to said work-support at opposite sides of said rib, means for progressively cutting the crest of the work-ridge lengthwise thereof, and mechanism for forming stitches disposed to maintain substantially the form of the work-ridge.

3. In a sewing machine, a work-support, work-feeding means, a ridge-forming rib disposed upon said work-support, a work presser opposed to said work-support at opposite sides of said rib, means for progressively cutting the crest of the work-ridge lengthwise thereof including a knife having its cutting edge opposed to and spaced from the crest of said rib, and mechanism for forming stitches disposed to maintain substantially the form of the work-ridge.

4. In a sewing machine, a work-support, work-feeding means, a pair of reciprocatory needles, a loop-taker cooperating with said needles in the formation of stitches, a ridge-forming rib disposed upon said work-support between the paths of reciprocation of said needles, a work-presser opposed to said work-support at opposite sides of said rib, and a ridge-scoring knife having its cutting edge opposed to and spaced from the crest of said rib.

5. In a sewing machine, work-feeding means, a work-support including a throat-plate provided with a needle-slot elongated transversely of the line of feed, a pair of reciprocatory needles operating through said needle-slot, a loop-taker cooperating with said needles in the formation of stitches, a ridge-forming rib upon said work-support and overhanging said needle-slot between the paths of reciprocation of said needles, a work-presser opposed to said work-support.

port at opposite sides of said rib, and cutting means adapted to progressively score the work in the portion thereof forming the crest of the work-ridge.

- 5 6. In a sewing machine, a work-support, work-feeding means, a ridge-forming rib disposed upon said work-support, a work-presser opposed to said work-support at opposite sides of said rib, a ridge-scoring knife opposed to and spaced from the crest of said rib, adjustable means for varying the spacing of said knife from said rib, and mechanism for forming stitches disposed in the work to maintain substantially the form of the work-ridge.
- 10 7. In a sewing machine, a work-support, work-feeding means, a ridge-forming rib disposed upon said work-support, a work-presser opposed to said work-support at opposite sides of said rib, manually operable means for lifting said work-presser away from said work-support, cutting
- 15 8. In a sewing machine, a work-support, work-feeding means, a ridge-forming rib disposed upon said work-support, a work-presser opposed to said work-support, means for reciprocating said work-presser toward and from said work-support, cutting means effective to score the work in the 15 portion thereof forming the crest of the work-ridge, and mechanism for forming stitches disposed with respect to said work-ridge to maintain substantially the form thereof.

MAX L. WATERMAN. 20

means effective in an operative position thereof to progressively score the work in the portion forming the crest of the work-ridge, operative connections for retracting said cutting means from its operative position upon actuation of said manually operable means, and mechanism for forming stitches disposed with respect to said work-ridge to maintain substantially the form thereof. 5
